UNITED STATES PATENT OFFICE.

JOHN L. C. HEINZ, OF CHICAGO, ILLINOIS.

SELF-LOCKING HINGE FOR CASEMENT WINDOWS.

Application filed April 13, 1925. Serial No. 22,511.

To all whom it may concern:

Be it known that I, JOHN L. C. HEINZ, a citizen of the United States, and a resident of the city of Chicago, county of Cook, and 5 State of Illinois, have invented certain new and useful Improvements in a Self-Locking Hinge for Casement Windows, of which the following is a specification.

My invention pertains to a self-locking 10 hinge for casement windows, and an object is to provide hinges with means which will permit the casement windows to be lowered on the outside of the window stool to make the window rainproof, and will likewise permit 15 the windows to be raised upwardly to clear said window stools and then to be swung inwardly. Another object is to provide such hinges with self-locking means for holding said windows in their lowered and 20 closed positions, and also for holding said windows in their raised position to be swung inwardly. And another object is to provide such hinges for casement windows which will lock the windows in their closed position 25 and will prevent them from being pried or jimmied open from the outside, and which hinges in conjunction with the usual turn-bolt or hasp will enable the windows to be locked in a slightly raised or opened position 30 without permitting opening of said windows from the outside. And a further object is to provide such hinges which are symmetrically constructed, so that they may be used interchangeably on either the right 35 hand or left hand window.

Other objects will appear hereinafter.

The invention consists in the combinations and arrangements of parts hereinafter described and claimed.

40 The invention will be best understood by reference to the accompanying drawings, forming a part of this specification, and in which,

Fig. 1 is an elevational view of a casement window showing my invention applied thereto, the left hand window being in its lowered and closed position, and the right hand window being in its raised position ready to be swung inwardly;

45 Fig. 2 is a vertical cross sectional view taken on line 2—2 of Fig. 1, showing the window closed, in full lines, and in dotted lines showing the window open;

50 Fig. 3 is an enlarged elevational view of the hinge mounted in position;

Fig. 4 is a horizontal cross sectional view taken on line 4—4 of Fig. 3, and showing the position of the hinge with the window both open and closed;

55 Figs. 5 and 6 show the parts of the hinge disassembled;

Fig. 7 is a cross sectional view taken on line 7—7 of Fig. 5; and

Fig. 8 is a detail view of the spring washer used in my hinge.

In the drawings I have shown my improved hinge in connection with a casement window including the swingable window parts 11 and 12, the part 11 being shown in its lowered or closed position and engaging 70 along the outward side of the window stool 13 of the window frame 14, while the part 12 is illustrated in its raised position adapted to be swung inwardly from the upper part of the window or transom 15, as indicated in dotted outline in Figure 2.

The improved hinge comprises two main parts 16 and 17, the part 16 having pintle barrels 18 adjacent its ends and spaced well apart, while the part 17 has a pintle barrel 19 mounted between said barrels 18 by means of a pintle 20 which may be provided with a fixed head 21 and a removable head 22 as indicated in Fig. 5, the pintle barrel 19 being shorter than the space between the pintle barrels 18 and permitting the hinge part 17 to be moved a considerable distance longitudinally of the hinge part 16 and the pintle 20. The hinge part 17 is preferably 85 constructed of a main part 17 and a part 17' 90 extending at an angle therefrom and being provided with suitable openings for receiving screws 23 or the like to fasten the part on the sash frame, as best indicated in Figs. 3 and 4; while similar openings are provided in the hinge part 16 to receive screws 24 for fastening said part 16 on the window frame. The hinge part 17 with the attached window is moved on the pintle 20 and 95 along hinge part 16 to lower the window back of the stool 13, and is moved upwardly to the upper part of the pintle to clear the window over the window stool and enable inward swinging thereof.

I provide means for locking the window 105 with the attached hinge part 17 in its lowered position, and also for locking or fastening the window with the attached hinge part in its upper position, and this means preferably comprises a member 110

adapted to engage the hinge part 17 and prevent upward or downward movement thereof longitudinally of the hinge part 16 and pintle 20. In the drawings I have shown this locking means including a curved member or finger 25 mounted on the hinge part 16 by means of a lip 26 engaging in a slot 27 provided at an intermediate portion of the hinge part 16. A spring 28 is fastened on the hinge part 16 and presses against the finger 25 to automatically hold it across either end of pintle barrel 19 on hinge part 17 in order to prevent upward or downward movement of said pintle barrel 19 along the pintle 20, a curved or raised part 25' being provided on the finger 25 for convenient engagement by a finger to press the same outwardly out of the path of the pintle barrel 19 and permit longitudinal movement of said barrel and the hinge part 17. A spring washer or split washer 30 is preferably mounted on the pintle 20 adjacent each pintle barrel 18 to provide resilience when the window is dropped with the hinge part 17 in its closed position.

This complete hinge is reversible and is mountable on either the right hand side or the left hand side of the window, in view of the fact that it is made entirely symmetrical, and this complete hinge is mounted preferably adjacent the lower side of the window, while the hinge placed at the upper part of the window is identical with the one described, but having the locking finger 25, and preferably also the associated spring 28, removed therefrom, in order that only one hand need be used for releasing the spring-pressed locking member 25 when the window is to be opened with the other hand.

It is apparent from the above disclosure that the finger 25 engages across the pintle barrel 19 and holds the same locked in its closed position, to prevent the window from being pried or jimmied open; and it is also apparent, that by pressing the finger 25 outward the pintle barrel 19 with the hinge part 17 and the attached casement window may be raised, and that thereafter the spring 28 presses the finger 25 automatically inward and beneath said pintle barrel, thus permitting the window to be swung open, inwardly from the transom 15; and furthermore that when the window is to be lowered into its closed position, that the finger 25 need merely be pressed back to permit the pintle barrel 19 and the attached window to be dropped into the closed position. With this construction of hinge, both of the casement windows may be placed in their raised but closed or joined position, by closing the turn bolt 31 which is mounted

on one window so as to engage the eye portion 32 mounted on the other window, and the two windows may be locked in position to provide a slight opening between the window stool and the bottom of the windows 11 and 12.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A hinge comprising swingably connected parts, one of said parts being movable longitudinally on the other, and means for locking one hinge part in position on the other, said hinge parts being constructed and arranged symmetrically so as to be reversible and mountable at either side of a window.

2. A hinge comprising a hinge part with spaced pintle barrels, a pintle in said barrels, another hinge part with a pintle barrel movable between the spaced barrels and longitudinally on said pintle, resilient means between each two of said pintle barrels and a finger swingably mounted on the first part at a certain position intermediate the spaced barrels and having a spring pressing it to engage across the ends of the pintle barrel on the second part and lock the latter barrel in position either above or below said swingable finger.

3. A hinge comprising a hinge part with spaced pintle barrels, another hinge part with a pintle barrel movable between said spaced barrels and longitudinally on the other hinge part, shock absorbing resilient means between each two of said pintle barrels, a finger swingably mounted on the first hinge part at a certain position intermediate the spaced barrels, and a spring pressing on said finger to automatically engage it across the ends of the pintle barrel on the second hinge part and to lock the latter barrel in position either above or below said swingable finger, said hinge parts being constructed and arranged symmetrically so as to be reversible and mountable at either side of the window.

In testimony whereof I have signed my name to this specification.

JOHN L. C. HEINZ.
